UNITED STATES PATENT OFFICE

JOHN K. RAUGSTAD, OF CHICAGO, ILLINOIS

JOINTED FIGURE TOY

Application filed December 10, 1931. Serial No. 580,134.

This invention relates to toys and more particularly to toys made of cardboard or the like in the similitude of animals or human beings in which the limbs are pivoted to the body and caused to move by pulling strings or by pulling connections attached to said limbs.

The general object of my invention is to provide toys of this character which can be made of either paper or wood, which can be in the form of "cut-outs" to be afterwards clipped from thin paper, pasted on cardboard and have the various parts put together to form what I term a "movie toy".

15 A further object is to provide a device of this character on which elastic bands are used for the purpose of returning the parts to their normal position after actuation and for the purpose of yieldingly connecting the actuating strings to the movable limbs of the toy.

Other objects will appear in the course of the following description.

20 My invention is illustrated in the accompanying drawings, wherein:—

Figure 1 is a front elevation of a toy constructed in accordance with my invention;

Figure 2 is a rear elevation thereof;

Figure 3 is a rear elevation of another form of toy embodied in my invention;

Figure 4 is a top plan view thereof.

Referring to these drawings in Figure 2, I have illustrated a doll constructed in accordance with my invention. In this figure, 10 designates the body of the doll having the usual head 11, the upper arms 12, the fore arms 13, the upper leg sections 14 and the lower leg sections 15. The arm sections 13 are connected to the arm sections 12 by means of the pivot 16 and the upper arm sections are connected to the shoulders of the body 10 by like pivots. The lower leg sections are connected to the upper leg sections by a pivot 16 and the upper leg sections are connected to the body by the same means.

Above the pivots 16 for the upper arms 12, the upper arms are provided with two apertures 17 preferably connected by narrow slits 18 to the edge of the arm section, thus permitting the introduction of a rubber band 19

between these arm sections. The upper ends of the upper leg sections 14 are also provided with the apertures 17 and slits 18 providing for the introduction of a rubber band 19 between these two sections. To the head is 55 attached a suspended loop 20 and to the rubber bands 19 is attached an operating cord 21 which extends down between the legs to any desired length. It will be obvious that when the body is suspended by the cord 20 and the 60 cord 21 is pulled, the legs and arms will be raised and when the tension on the cord 21 is relaxed, the arms and legs will return to their normal position.

In Figure 3, I illustrate the figure of an 65 animal having the same general principle as illustrated in Figure 2. For illustration, I have shown the figure in the form of a horse, 22 designating the body of the horse, 23 the neck and head, 24 the tail, 25 a fixed fore leg, 26 a movable fore leg, and 27 two connected movable hind legs. The neck is pivoted to the body at 28. The tail is pivoted to the body at 29, the fore leg is pivoted to the body at 30 and the hind legs are pivoted at 31. 70 These pivots, as in the former case, may be in the form of rivets, fasteners, eyelets, or other like devices.

75 It will be noted that the root portion 24a of the tail is formed above the pivot 29 with 80 two openings 31a, one of these openings having a slit extending into the opening. The neck 23 on each side of the pivot 28 is formed with the openings 32 and 33. A rubber band 34 is engaged in the openings 31a and 32 and a rubber band 35 which is preferably formed of one strand of rubber and knotted at its ends is engaged with the opening 33 and the lowermost opening of the tail. The joined 85 hind legs 27 at their upper end above the pivot 31 thereof are provided with an opening 36 while the upper end of the fore leg 26 is provided with an opening 37. Slits 90 lead from the upper edges of these sections to said openings so as to provide for the ready insertion of a rubber band 38 in these openings.

95 Threaded through openings 39 and 39a in the body of the animal is a rubber band 40, one end or strand of which extends to an 100

opening 41 in the hind leg of the animal while the other strand extends into an opening 41a in the movable fore leg of the animal, the opening 41 and the opening 41a being disposed below the pivots for the jointed hind legs and for the fore legs. Attached to the body of the animal is a suspending loop 42 and attached to the rubber bands 34 and 38 is an operating cord 43. It will be obvious now that when the body is suspended by the cord 42 and the cord 43 is pulled that the head and neck of the horse will be rocked upon the pivot 28, the fore leg 26 will be advanced, the hind legs will be thrown rearward, the tail will be raised and that upon relaxing the tension upon the cord 43, the rubber bands will retract the parts to their original position. In other words, the pull on the cord 43 pulls the head up and the tail up against the tension of the rubber band 35 while the pull on the cord 43 pulls down on the rubber band 38 and places a tension upon the rubber bands 40 and as soon as the pull on the cord 43 is relaxed, the bands tend to return the parts to their original position.

It will be seen that I have provided toys which may be cheaply made and which may very effectively be made. These toys may be printed on paper and then cut out and put together by a child or may be initially cut out and put together by machinery or other means.

I claim:—

A toy of the character described in the form of an animal, the toy comprising a body, a head and neck pivoted upon the body, a tail pivoted upon the body, a fore leg pivoted upon the body and hind legs pivoted upon the body and joined to each other, an elastic band connecting the neck on one side of the pivot thereof to the tail on one side of the pivot thereof, an elastic band connecting the fore leg to the hind leg on one side of the pivots thereof, a pull cord attached to said rubber bands, elastic bands engaged with the fore leg and hind legs and with the neck and the tail and acting to retract them to a normal position.

In testimony whereof I hereunto affix my signature.

JOHN K. RAUGSTAD.
